UNITED STATES PATENT OFFICE.

DAVID E. EVANS, OF VENEDOCIA, OHIO.

FOLDING CRATE.

SPECIFICATION forming part of Letters Patent No. 352,183, dated November 9, 1886.

Application filed August 20, 1886. Serial No. 211,387. (Model.)

To all whom it may concern:

Be it known that I, DAVID E. EVANS, a citizen of the United States, residing at Venedocia, in the county of Van Wert and State of Ohio, have invented certain new and useful Improvements in Folding Crates; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to folding crates; and it consists in the novel features more fully hereinafter set forth and claimed, and shown in the annexed drawings, in which—

Figure 1 is a side view of the crate set up and ready for use. Fig. 2 is a plan view showing the cover removed. Fig. 3 is a section on the line X X of Fig. 2. Fig. 4 is an end view, and Fig. 5 is a side view, parts broken, showing it in a folded position.

The crate comprises the bottom A, ends B, sides C, and top or cover D. The bottom is provided with an upwardly-projecting rim, A', sufficiently high to inclose the ends B and side C of the crate when folded. It projects from near the edges of the bottom, and is composed of end sections, a, and side sections, a'. The sides and ends are supported directly upon the upper edge of the rim. The lower edges of the ends B are provided with battens b, and the upper edge of the end sections, a, are strengthened by corresponding battens, b'. The proximate edges of the battens are in the same plane, and are held together by hooks d and eyes d'. The upper edges of the ends have battens b² to receive strips d², depending from each end of the cover. The battens b² are at a distance from the edge corresponding with the width of the strips d², which overlap the sides and prevent longitudinal displacement. The cover is held in place at one end by hooks and eyes similar to those for holding the ends to the bottom, and at the other or both ends by a bent fastener, e, depending from the strip d², fitting in a groove, e', cut in the batten b², and having its bent end turned to engage with the under side of said batten b². The bent fastener e is secured to the cover in such manner as to

rotate about its shank as an axis, in order to be engaged with or disengaged from the batten. When the bent end is turned to register with the groove, the cover may be disengaged by elevating the end provided with the bend sufficiently far to disengage the hooks and eyes at the opposite end, about which it turns as a hinge during this movement. When the bent end is turned to engage the under side of the batten, the top is fastened, as will be readily understood.

The inner lower corners of the sides C have plates or battens of wood, F, fastened thereto, the lower ends of which, projecting beyond the edges of the sides and extending a short distance within and overlapping the inner portion of the side sections, a', of the rim A', hold the sides from outward displacement at the lower edges when set up. Their inward displacement is prevented by bearing against the edges of the ends and intermediate partition or partitions. The outward displacement of the upper edges is prevented by straps, G, secured to the upper edges of the ends and partition and having their outer ends, g, bent downward and embracing the edges. The plates F have flanges f bent inward toward each other to resist and limit the inward pressure or movement of the ends, (or the wooden blocks have squared edges to answer the same purpose.)

In case it is desired to divide the crate, a partition, H, constructed like one of the ends is provided and held at the desired point between flanges f' of the plates or battens F', which are constructed like plates or battens F, the lower ends projecting beyond and overlapping the side sections, a', of the rim A'. The partition rests upon a strip, h, secured to the bottom of the crate.

In setting up the crate the farther side is placed up; then the partition is placed up, then the other side put up, so the partition-hooks will embrace both sides. Then either end can be secured to the bottom by the hooks and eyes, and brought up so that the hooks or bent ends will embrace the sides. The crate being filled, the cover is hooked at one end, turned down, and secured at the other by turning the bent end of the fastener e under the batten b². For reshipping the crate, the reverse operation is practiced in taking it apart. The ends are

packed on each side of the central strip, *h*, the upper and lower edges being placed parallel with the sides of the bottom. The partition is placed on top of one of the ends, with the 5 edge having the straps at right angles to the length of the bottom, cuts *l* being formed in the upper edge of the side sections, *a'*, of the rim to permit the passage of the ends of the straps *G*. As the side sections of the rim *A* 10 are thicker than the sides *C*, a portion is removed at one side of the cuts *l*, forming a recess, *l'*, in which the ends *g* rest, (or the partition is made in two pieces, so it will go inside like the ends.) The sides are placed on top the 15 partition; and, lastly, the cover is hooked at one end and secured at the other end by the bent fastener *e* to the batten *b'* in a manner similar to that by which it is secured to the batten *b*² when the crate is set up; or both ends 20 of the cover may be secured by bent fasteners.

Having thus described my invention, what I claim, and desire to secure by Letters Patent, is—

1. The combination of the bottom having an 25 upwardly-projecting rim, and cuts formed in the upper edges of its opposite side sections, and a partition having straps secured to its upper edge for embracing the sides, and adapted to lie in said cuts when the crate is folded, 30 substantially as and for the purpose set forth.

2. The herein-described crate, consisting of the bottom, the ends having battens near the upper edge projecting on each side, the sides fitting against the edges of the ends and having

the projecting ends of the battens bearing upon 35 their end edges, straps secured to the upper edges of the end pieces and extending over, bent down upon, and embracing the upper edges of the sides, and the cover secured at one end by hooks and eyes, and at the other 40 end by a bent fastener fitted in a groove in the batten and turned under the same, substantially as set forth.

3. The herein shown and described folding 45 crate, consisting of the bottom having an upwardly-projecting rim, the end pieces resting upon the end sections of the rim, battens secured to the proximate edges of the end pieces and rim-sections, hooks and eyes for securing the ends to the rim-sections, the sides, flanged 50 plates (or battens of wood) secured to the lower inner corners of the sides and projecting within the rim, straps secured to the upper edges of the end pieces, and having their outer ends bent down over and embracing the 55 upper edges of the sides, and the cover secured at one end by hooks and eyes, and at the other end by a bent fastener fitting a groove in a batten secured near the upper end of the end piece, and turned to engage the under side of 60 it, substantially as set forth.

In testimony whereof I affix my signature in presence of two witnesses.

DAVID E. EVANS.
